HYDRAULIC LOG BARKING APPARATUS

William H. Rambo and Harold A. De Rice,
Portland, Oreg.

Application July 28, 1947, Serial No. 764,060

6 Claims. (Cl. 299—66)

1

Our present invention comprises means for barking a log hydraulically or cleaning the surfaces of logs or the like, or hydraulically cleaning, scrubbing or otherwise utilizing a jet or spray of water or other fluid to perform a useful operation upon the surface of a long object such as a log.

The principal object of the present invention is to provide means for hydraulically debarking logs, for cleaning logs or the like, or for spraying similar articles, in a machine having means for automatically, completely operating upon the entire surface of the log or similar article. This object of the present invention is achieved by providing novel, easily built and operated means for directing a jet or spray against the surface of a log or the like, while producing such relative movement of the log or the like, and jet or spray as to completely traverse the entire surface of the log or the like.

A further principal object of the present invention is to provide means whereby relative movement of a log and a jet producing debarking nozzle is achieved hydraulically, thus making it possible to utilize the means for creating a high-pressure jet as the means for producing relative movement of the log and nozzle.

A further object of the present invention is to provide hydraulic debarking means of sturdy character, assembled from relatively simple and sturdy parts of light weight, the combination having a high degree of resistance to damage by the destructive force of a high-pressure jet and being relatively unsusceptible to damage by pieces of bark, wood, stones or other debris occasionally projected with great force by hydraulic debarking nozzles.

A further object of the present invention is to provide hydraulic debarking apparatus which may be controlled from a safe distance so as to eliminate injury to workmen engaged in cleaning or debarking logs.

A further object of the present invention is to provide debarking, cleaning or spraying apparatus which is quickly and easily adjustable to accommodate various lengths and diameters of objects being operated upon.

A further object of the present invention is to provide a hydraulic debarking, cleaning or spraying mechanism wherein a nozzle reciprocates the length of a log or similar object to be debarked, cleaned or sprayed, characterized by novel means for controlling the reciprocations of the nozzle automatically or manually as desired.

The foregoing and other objects and advan-

2

tages of the present invention will be more readily apparent from inspection of the accompanying drawings taken in connection with the following specification wherein like numerals refer to like parts throughout. In the drawings Fig. 1 is a plan view, partially schematic in character, of the essential portions of a preferred embodiment of our invention; Fig. 2 is a vertical section taken substantially along line 2—2 of Fig. 1, the view being on an enlarged scale; Fig. 3 is a vertical section through a portion of the present invention taken substantially along line 3—3 of Fig. 1 with the nozzle reciprocated to the other end of its normal path of movement from the position illustrated in Fig. 1, and approaching the end of its normal travel; Fig. 4 is a vertical section on an enlarged scale taken substantially along line 4—4 of Fig. 3 with parts broken away; Fig. 5 is a vertical section taken substantially along line 5—5 of Fig. 4; and Fig. 6 is a schematic view of a modified form of the invention.

In the preferred embodiment of the invention a ramp 10 is provided upon which a log may be placed by any suitable means, the ramp sloping downward so that the log will roll towards its lower edge until stopped by a plurality of dogs 11 mounted upon a shaft 12 adjacent the lower edge of the ramp. The dogs 11 are fastened to the shaft 12 so that all may be rocked from the position illustrated in full lines in Fig. 2 to the position illustrated in dotted lines by means of a hydraulic cylinder 13 having a piston rod 14 pivotally connected to one of the dogs. Extensions 15 on the dogs project above the runways 35 of the ramp 10 when the dogs release a log and permit it to roll forward, the projections thus acting as means to prevent the advance of a succeeding log. When the dogs 11 are released and rocked forwardly they provide means to bridge a gap between the ramp 10 and log retaining and rotating means including a lower ramp 20. As seen in Fig. 2, a log 21 has been advanced onto the upper edge of the lower ramp 20 and is seated in a plurality of cradles formed by lengths of sprocket chains 22 passing over sprockets 23 mounted upon arms 24, and a plurality of sprockets 26 fixed to shafts 27 at the upper corner of the ramp 20. Also fixed to the shafts 27 are a plurality of rollers 28 of larger diameter than the sprockets 26. The arms 24 are downwardly curved so that they will not contact the logs as the latter force the chains to sag between the sprockets 23 and 26. In this condition the rollers 28 project above the lower stretches of the sprocket chains and provide means to prevent the log from

rolling back toward the gap between the ramps. The arms 24 are attached to piston rods 30 of a plurality of hydraulic cylinders 31 so that the position of the arms may be adjusted from the full line position shown in Fig. 2 to a lower position such that the sprockets 23 are retracted beneath the ramp 20, or other raised positions so that logs of various diameters may be retained in contact with the rollers 28.

The sprocket chains 22 pass about the sprockets 23 and 26, then about sprockets 35 mounted upon posts 36, then about floating sprockets 37 vertically movable in guides 38, then about sprockets 39 mounted beneath the ramp 20, and back to the sprockets 23. The sprockets 37 are supported on the ends of levers 40 pivotally mounted at 41 upon uprights 42, the forward ends of the levers being slotted to permit vertical movement of the sprockets 37 so that as the sprockets 23 are raised or lowered the sprockets 37 will automatically take up any slack in the sprocket chains. Proper tension is always maintained by piston rods 43 extending to levers 40 from cylinders 44.

The sprockets 35 are mounted upon separate shafts, each of which has affixed thereto a sprocket 45 (see Fig. 1) from which extends a sprocket chain 46 to sprockets 47 (see Fig. 2) on a power shaft or shafts 48 connected to suitable sources of power (not herein illustrated). Rotation of the shaft 48 thus produces rotation of the sprockets driven by chain 22 and the rollers 28 so that the log 21 may be intermittently or continuously rotated about its longitudinal axis while resting in the cradles provided by the chains 22.

It is preferred that sprockets 35 and sprockets 47, as well as the sprockets 26 and rollers 28, are mounted upon individual shafts so that each chain 22 can operate independently of the others to permit operation of the chains at varying velocities to accommodate tapered logs or other objects of nonuniform diameter. The purpose of this is so that shorter lengths of logs may be handled by operating less than all of the chains and longer lengths by operating all of the chains. If desired all of the chains could be interconnected so as to eliminate separate controls for each chain.

A hydraulic nozzle 50 is mounted in the gap between the upper ramp 10 and the lower ramp 20 and is adapted to be reciprocated lengthwise of the log, either while the log is stationary between intermittent movements, or while the log is slowly rotating. In the first case longitudinal elements of the log will be stripped of bark and cleaned, and in the second case, spiral elements of the log will be stripped of bark and cleaned. In either event, the nozzle is adapted to be automatically reciprocated from end to end of a path designed to cover the longest log for which the machine is designed, or manually controlled to reciprocate through shorter paths to accommodate shorter logs. Also, the angle of impact of the jet with the log may be adjusted as desired while the jet is in operation so as to change the angle of impact for most efficient operation, or to accommodate the mechanism to logs of various diameters.

Referring to Figs. 1, 2 and 3 it will be seen that the nozzle 50 comprises a vertical stem 51 which is attached to the vertical leg of a T-fitting passing through a longitudinal slot 52 in the top of a shield 53 which is supported between adjustable end plates 54. The end plates 54 are mounted upon fixed plates 55 supported by any

suitable means (not herein shown). The lower edges of the end plates 54 are provided with arcuate racks 56 meshing with a pair of pinions 57 mounted upon a shaft 58 extending between the fixed plates 55, one end of which is provided with a crank 59 or suitable means, by means of which the shaft 58 may be rotated to adjust the position of the end plates 54 with respect to the plates 55. The plates 54 are pivotally mounted upon studs 60 placed about concentric openings through plates 54 and 55 and which are threaded for the reception of nuts 61 which may be tightened if desired to fix the two plates in adjusted position. In order to permit relative rotation of the plates the studs 60 pass from plates 55 through arcuate slots 62 in the movable plates 54.

A hollow, open-ended, piston rod 65 extends through superimposed concentric openings in each set of end plates 54 and 55, the outer end of each piston rod 65 passing through a packing gland 66 at the end of a long cylinder 67 with which communicates the end of a supply pipe 68. The end of the hollow piston rod 65 with 25 in the cylinder 67 is provided with a piston head 70 of larger diameter than the outer diameter of the hollow rod 65 and of such diameter as to hydraulically seal a hollow space 71 between the outer wall of the hollow rod 65 and the inner wall of the cylinder 67. The inner end of the hollow piston rod 65 communicates with the T-fitting 72 leading to the nozzle 50.

The construction set forth in Fig. 3 is duplicated at the opposite end of the shield 53 as seen in Fig. 1 so that water under pressure enters the T-fitting 72 from both ends, the pipes 68 being connected to a pump 75 for creating high pressure, such as 1500 pounds per square inch. The constructions at each end of the fitting 72 are carefully matched and balanced so that the pressures existing within the pipes 68 cancel each other and the fitting 72 will not be moved in either direction as a result of pressure from pump 75.

The spaces 71 communicate through passages 73 with pipes 80 leading from a pump 81. If the pump 81 is permitted to force water under its pressure into the space 71 at the right of the mechanism the enlarged head 70 on the hollow rod 65 will act as a piston to pull the nozzle 50 toward the right end of the shield 53 (see Fig. 1); and if the output of pump 81 is introduced into the left end of the construction the nozzle will be pulled toward the left end of shield 53 (see Fig. 3).

In order to provide means for controlling the direction of movement of the nozzle we provide control means including a valve rod 82. The valve rod 82 carries thereon a first valve disk 83, a second valve disk 84 and a piston head 85 at each end. The disk 83 is so mounted as to be movable to one side or the other of the passage 73, thus permitting the space 71 to be placed in communication with the inlet pipe 80 from pump 81, or an exhaust pipe 86. This movement may be accomplished by causing the piston head 85 to be acted upon by fluid entering its cylinder through either pipe 90 or pipe 91 from a suitable source 92 as controlled by a four-way valve 93. When the valve is in one position the space at one side of piston head 85 may be exhausted through an exhaust opening 94 and pressure applied to the opposite side, or vice versa. As seen in Fig. 3 pressure has been applied through pipe 90 to move piston head 85 toward the right

to position the disk 83 at the right of passage 73 so that pressure from pump 81 is moving the nozzle 50 toward the left. At any time in the travel of the nozzle the valve 93 may be rotated to exhaust the space to the left of piston head 85 and apply pressure against its other side to move piston rod 82 toward the left so as to place the disk 83 to the left of passage 73. Pressure from pump 81 is thereby shifted to the piston 70 at the opposite end and thereupon moves the nozzle toward the right while the space 71 shown in Fig. 3 is exhausted through pipe 86. The second disk 84 is provided in order to have balancing pressure to negative the pressure against disk 83.

In order to provide automatic means for controlling the nozzle 50 we provide an over-center spring trip at each end of a valve control rod, one of which is fully illustrated in Figs. 4 and 5. In these figures it is seen that the T-fitting 72 is mounted upon a carriage 100 provided with a pair of flanged wheels 101 riding upon tracks 102 fixed to the upper surfaces of I-beams 103 extending between the adjustable end plates 54. The central portion of the carriage 100 supports a sleeve 105 which embraces a valve control rod 106. This rod is slidably mounted in bosses 107 extending inward from the end plates 54. Each plate 54 has a support 108 welded thereto upon which are mounted an upper bolt 109 and a spaced pair of lower bolts 110. These bolts support a forward plate 111 held in spaced relation thereto by suitable spacers surrounding the bolts as seen in Fig. 4. A pair of depending arms 113 are pivoted individually and coaxially upon and between the support 108 and the plate 111 by pivots 112, the lower ends of the arms being joined by a pin 114 and an extension 115 embracing valve rod 82. The upper ends of the arms are spaced from each other to provide clearance for a spring 116 stretched between the pin 114 and a movable member 118, the point of attachment of the upper end of the spring 116 being above the pivotal attachment of the arms 113 to their supporting members 109 and 111. The movable member 118 is provided with a longitudinal slot 120 through which the bolt 109 passes, and is also provided with a pair of forwardly extending arms 121 which pass beyond the edges of plate 111 at a distance therefrom and are adjustably fastened to the valve control rod 106. The extension 115 is provided with an arcuate slot 122 through which the valve rod 82 passes, the arcuate slot being provided to permit rotation of the end plates 54 to which the supports 108 are attached. It will be seen in Figs. 4 and 5 that the movable end plate 54 is provided with an adequate slot 123 for the same purpose, while the fixed end plate 55 is provided with a clearance opening 124 for the valve rod 82. A pair of collars 125 and 126 are adjustably fastened to the valve rod 82, one at each side of the extension 115.

When the carriage 100 moves to the left a short distance from the position illustrated in Fig. 5 the sleeve 105 strikes the forward arm 121, thus moving the movable member 118, as permitted by the slot 120 and the end of the rod 106 sliding through the boss 107. This moves the upper end of the spring 116 over center with respect to the pivotal attachment of the arms 113 to thereby cause the spring 116 to snap the arms 113 and the valve rod 82 toward the left. In so doing the land 83 is moved to the left of the passage 73 while the second land 84 is moved further toward the left in its cylinder. The movement is

adjustably determined to position the land 83 between the passage 73 and the inlet pipe 80, thus stopping the flow of fluid under pressure into the space 71 and opening the exhaust passage 86. Since this movement of the valve 82 has also caused a reversed relationship of the corresponding parts at the opposite end of the construction, the piston head 70 at the right of the construction will draw the carriage 100 toward the right. The over-center device illustrated in Fig. 5 is also duplicated at the right end of the construction and the corresponding members attached to the opposite ends of the rods 106 and 82 have been similarly moved towards the left to prepare the right end over-center device for reversing action as soon as the carriage 100 reaches the right end of its travel. It is to be appreciated that the cylinder occupied by the piston head 85 is emptied and open to the atmosphere during automatic operation so that the valve rod 82 may not be locked in position by the piston head 85. It is also to be appreciated that the pressure of the pump through the pipe 80 against the first land 83 is balanced and negated by the pressure against the second land 84 so that the valve rod 82 will always be ready to move in either direction regardless of which end of the carriage is being subjected to pressure from the pump 75.

As seen in Fig. 1 the pipes 68 may be connected to the pipes 80 through the medium of a branch pipe 130 controlled by a throttling valve 131 so that the one pump 75 may operate to supply pressure to both the nozzle and the nozzle carriage moving means if desired.

In Fig. 2 it is seen that the space beneath the log and nozzle may have sloping floors, as indicated at 140 and 141, converging toward an endless belt 142 passed about pulleys such as the pulley 143 and caused to move by suitable means (not shown) in order that bark and other waste may be carried away from the construction.

In Fig. 6 we have schematically represented a modified form of our invention in which the nozzle 150 is the terminus of a reversely bent fixture 151 projecting through a slot 152 in the side of a shield 153 remote from the log in order to minimize the chances of chips of barking fouling the mechanism.

We have herein illustrated embodiments of our invention wherein certain details are schematically illustrated and other details are illustrative of one embodiment which certain portions may assume. It is to be appreciated that various modifications in arrangement and detail may be achieved by those skilled in the art. All such modifications as come within the true spirit and scope of the appended claims are considered to be part of our invention.

We claim:

1. A machine for performing operations upon a long object, such as debarking a log, comprising a nozzle, a carriage supporting said nozzle, a pair of hollow, open-ended piston rods communicating at one end with said nozzle and extending from said carriage in opposite directions, an annular piston fixed to and coaxially surrounding each of said hollow piston rods, a cylinder surrounding each hollow piston rod in spaced relation and confining each of said pistons, fluid pressure creating means, a fluid directing system connecting said fluid pressure creating means with the interiors of both of said cylinders beyond said pistons and also with the spaces between said hollow piston rods and said cylinders, said system supplying pressure fluid to the interiors of both of said

hollow piston rods to be ejected therefrom through said nozzle, and valve means included in said system, said valve means being movable to alternate positions effective alternately to connect one of said spaces to said fluid pressure creating means while relieving the other to atmosphere in order to effect reciprocation of said carriage.

2. The structure set forth in claim 1; in combination with automatic valve tripping means connected to said valve means and engageable by said carriage at the end of each reciprocatory movement thereof for effecting the alternate positioning of said valve means.

3. In a machine for directing a high pressure jet against an object, such as a machine for debarking a log, a carriage, guides for guiding said carriage, a nozzle supported by said carriage, a pair of equal conduits leading to said nozzle from opposite sides thereof, a single means for supplying fluid under high pressure simultaneously through both of said conduits, a pair of hydraulic piston means each extending parallel with said guides from a side of said carriage, one in opposition to the other, and means to supply fluid under pressure alternately to each of said piston means while relieving the other whereby to reciprocate said carriage along said guides.

4. In a machine for directing a high pressure jet against an object, such as a machine for debarking a log, a carriage, guides for guiding said carriage, a nozzle supported by said carriage, a pair of equal conduits leading to said nozzle from opposite sides thereof, a single means for supplying fluid under high pressure simultaneously through both of said conduits, a first hydraulic piston means extending parallel with said guides from a side of said carriage, a second hydraulic piston means extending parallel with said guides from the opposite side of said carriage, means to supply fluid under pressure alternately to each of said piston means while relieving the other whereby to reciprocate said carriage along said guides including a valve associated with each of said pistons, and valve actuating means connecting said valves and engageable by said carriage at each end of its travel.

5. In a machine for directing a high pressure jet against an object, such as a machine for debarking a log, a carriage, guides for guiding said carriage, a nozzle supported by said carriage, a pair of equal conduits leading to said nozzle from opposite sides thereof, a single means for supply-

ing fluid under high pressure simultaneously through both of said conduits, a first hydraulic piston means extending parallel with said guides from a side of said carriage, a second hydraulic piston means extending parallel with said guides from the opposite side of said carriage, means to supply fluid under pressure alternately to each of said piston means while relieving the other whereby to reciprocate said carriage along said guides including a valve associated with each of said pistons, and valve actuating means engageable by said carriage at each end of its travel, said valve actuating means including a valve rod operatively connected to both of said valves.

6. In a machine for directing a high pressure jet against an object, such as a machine for debarking a log, a carriage, guides for guiding said carriage, a nozzle supported by said carriage, a pair of equal conduits leading to said nozzle from opposite sides thereof, a single means for supplying fluid under high pressure simultaneously through both of said conduits, a first hydraulic piston means extending parallel with said guides from a side of said carriage, a second hydraulic piston means extending parallel with said guides from the opposite side of said carriage, means to supply fluid under pressure alternately to each of said piston means while relieving the other whereby to reciprocate said carriage along said guides including a valve associated with each of said pistons, and valve actuating means engageable by said carriage at each end of its travel, said valve actuating means including a valve rod operatively connected to both of said valves and a pair of over-center spring, snap-acting levers connected to said rod, one of said levers being located at each end of said guides.
